UNITED STATES PATENT OFFICE

WILLIAM D. HICKS, OF INGLEWOOD, CALIFORNIA, ASSIGNOR, BY MESNE ASSIGNMENTS, TO MASTER WIRE LATH COMPANY, OF LOS ANGELES, CALIFORNIA, A CORPORATION OF CALIFORNIA

LATH

Application filed July 14, 1923, Serial No. 651,673. Renewed June 8, 1928.

This invention particularly pertains to a metal lath.

An object of the invention is to provide a wire lath having the qualities of strength, 5 flexibility, and lightness, and which is adapted to be manufactured at small cost, which may be easily and quickly applied, and which is adapted to be employed either as an exterior or interior lath.

10 Another object is to provide a construction whereby wire netting, such as the ordinary poultry wire of commerce, may be employed as a lath, and a particular object is to provide means whereby the netting may be readily applied to and affixed on a support and the major portion of the netting spaced from the surface of the support so as to afford a bond and a reenforcement for a plastic coating.

15 Another object is to provide a fabricated lath as an article of manufacture comprising a panel embodying a flexible backing sheet and a wire netting applied to the backing sheet to form a unitary structure whereby the backing sheet and the wire structure may be applied simultaneously to a framework or other suitable support, and in which the major portion of the wire structure will be maintained in spaced relation to the backing sheet 20 to afford a bond and reinforcement for plaster.

25 With the foregoing objects in view, together with such other objects and advantages as may subsequently appear the invention resides in the parts and in the construction and arrangement of parts hereinafter described and claimed and illustrated in the accompanying drawings, in which:—

30 Figure 1 is a perspective view illustrating a fragmentary portion of a sheet of the lath showing the plaster coating as applied to a portion thereof.

Fig. 2 is a detail in vertical section showing the lath as applied.

35 Fig. 3 is a detail in perspective showing a manner of attaching the wire netting to a backing sheet.

40 Fig. 4 is a detail in section illustrating another manner of fastening the wire netting to a backing sheet.

Fig. 5 is a detail in perspective illustrating a further manner of fastening the wire netting to a surface.

More specifically, 7 indicates a wire netting which may be of any suitable construction but is here shown as comprising ordinary woven wire, commonly known as poultry wire, in which lengths of wire are joined together to form a mesh having hexagonal shaped interstices arranged in parallel rows, 55 the individual interstices of adjacent rows, being staggered with relation to each other. The adjoining sides of the interstices are defined by twisted strands of the wire, as indicated at 8 in the drawings. There will then be a twisted strand of wire along opposite sides of each of the interstices and connecting the adjacent corners thereof. In carrying out my invention, a sheet of the wire netting is acted upon so as to deform the otherwise straight twisted portions 8 to thereby form protrusions substantially U-shaped, which project from the plane of one side of the sheet of netting as indicated at 9. These 60 projections are adapted to seat upon and rest against the surface of a backing sheet 12, and thus afford means for positively spacing the major portion of the netting from the surface of the backing sheet and in fixed relation thereto.

65 Attention is directed to the fact that the projecting portions of the netting are formed of the double twisted strands of wire. These double or thickened portions rest against the supporting surface of the backing sheet and when fastened at these points to the backing sheet as herein described will not punch through the sheet due to the wide area of their contact surfaces.

70 In forming the lath so that it may be mounted on spaced supports as on studding, ceiling beams, and the like, the backing sheet 12 preferably consists of an imperforate sheet of flexible fibrous material such as heavy paper. The netting may be affixed to the surface of the sheet 12 in any desired manner, such for example as by means of staples 13 as 75 shown in Fig. 3, which staples extend astride the crotch of the U-shaped projections 9, and are passed through the sheet 12 after which 80

the ends of the staples are clinched over the back of the sheet as indicated at 14. The netting may be also attached to the backing sheet by means of stitching as shown in Fig. 4; a cord 15 being passed back and forth through the sheet 12 and engaged with the projections 9 on the netting. Another form of attachment consists of wires or threads 16 extending transversely of the netting and arranged in the U-shaped projections 9 as shown in Fig. 5, which wires or cords are fastened through the sheet 12 by staples or stitching 17. In any event the wire netting will be positioned in positive spaced relation to the backing sheet at all times and the method of fastening the netting to the backing sheet will render the backing sheet substantially imperforate. This will insure that the strength of the backing sheet will be preserved and that it will be an effective barrier to mortar or moisture which would pass through a perforate backing sheet.

When desired the sheet with the wire netting affixed thereto may be dipped in a liquid such as asphaltum so as to coat the backing sheet and the netting with a non-absorptive material. This material will also close any small perforations formed through the backing sheet incident to the stitching or fastening operation, if such perforations should accidentally occur, thereby rendering the assembled lath structure fully waterproof. The coating material indicated at 18 is adhesive in character and is applied in such thickness as to form a bond for a fragmentary material 19 which is applied to the coating while the latter is soft. The fragmentary material 19 may be of granular character such as calcined diatomaceous earth, or may consist of a suitable fibrous material or may comprise both a granular and a fibrous material. This fragmentary matter being highly absorptive of moisture serves as a bond for a plaster coating 20, whereby the plaster will be anchored to the surface of the backing sheet as well as held and reinforced by the netting which is completely embedded within it.

The sheet lath thus formed may be secured to studding 21 or other suitable frame-work by nails 22 which are driven thru the backing sheet alongside of the projections 9 and clinched over the projections as shown in Fig. 1. The backing sheet thus affords means whereby the lath may be mounted to span open spaces as it affords a backing for the plaster coating 20; the backing sheet being tied throughout at comparatively close intervals to the wire netting so as to inhibit its being pressed away from the latter. The adhesive coating in which the wire netting and the backing are embedded serves to securely retain the backing sheet and netting in their connected condition. The lath is of such rigidity that it may be carried on a framework of spaced supports but is of such flexible char-

acter that it may be bent to form curved surfaces such as the curved faces of arches, coves and rounded corners, and is admirably suited as a lath for round columns and curved walls.

By forming the wire netting as here set forth the major portion of the netting will be positively held in spaced relation to the backing at all times so that when plaster is applied thereto a substantial body of plaster will extend between the netting and its backing surface as shown in Figs. 1 and 2, completely embedding the same and thus providing a strong support and reinforcement for the plaster. By affixing the wire netting to the backing sheet a unitary structure is formed whereby the backing sheet and wire may be applied to a framework or surface at one operation.

I claim:

1. A lath comprising a wire netting formed with projections on one side thereof, a flexible sheet support for said netting on which said projections are seated to hold the major portion of the netting in spaced relation to the support, means for fastening the netting to the support, and a non-absorptive adhesive material on the surface of said support and coating said netting, and a fragmentary material carried by said adhesive coating.

2. A lath as an article of manufacture comprising a flexible backing sheet of fibrous material, a wire netting of open mesh having projecting loop portions extending from one side thereof which seat on said sheet, means for fastening the sheet and netting together to form a unitary structure, said means embodying fastenings to connect the loops to the sheet, a body of adhesive material applied to said netting and the sheet serving to cause the netting and sheet to adhere together, and an absorptive material imposed on said adhesive material.

3. A lath as an article of manufacture comprising a flexible backing sheet of fibrous material, a wire netting of open mesh having projecting loop portions extending from one side thereof which seat on said sheet, means for fastening said sheet and netting together passing through said sheet and over the loop portions of the netting, and a surface coating of non-absorptive adhesive material on said sheet and netting, said coating embedding said fastening means cooperating therewith in effecting connection of the loop portions of the netting to the backing sheet.

4. An article of manufacture comprising an imperforate backing sheet, a strip of wire netting covering the same adjacent strands of wire being twisted together to form twisted lengths and intervening interstices, spacing means formed by protruding the twisted lengths from one face of said netting which portions are adapted to rest against one face of the backing sheet, and means for fastening said spacing means of the netting to said

backing sheet at the points of contact therewith.

5. An article of manufacture comprising a backing sheet, a sheet of wire netting disposed thereover, a plurality of protrusions spaced longitudinally and transversely from each other formed by strands of said netting and resting against the face of said backing sheet to hold said netting and backing sheet 10 in spaced parallel planes, and means engaging the protrusions to fasten them in fixed relation to the backing sheet.

6. An article of manufacture comprising a flexible fibrous backing sheet, a flexible sheet of woven wire netting disposed thereover, a plurality of protrusions spaced longitudinally and transversely from each other formed by strands of said netting and resting against the face of said backing sheet to hold said 15 netting and backing sheet in spaced parallel planes, and means engaging the protrusions to fasten them in fixed relation to the backing sheet.

7. A lath comprising a sheet of metallic mesh-like material formed with loop portions spaced longitudinally and transversely from each other extending from one side thereof, a flexible fibrous backing sheet upon which said extended loop portions are seated 20 to hold the major portion of the mesh-like material in spaced relation to said backing sheet, and means for fastening the netting to said backing sheet.

8. A lath comprising a wire netting of open mesh having projecting loop portions spaced longitudinally and transversely from each other extending from one side thereof, a fibrous backing sheet in contact with said projecting loop portions, and means for fastening 30 said backing sheet and netting together at said points of contact.

9. A lath comprising a wire netting of open mesh having projecting loop portions spaced longitudinally and transversely from each other extending from one side thereof, a fibrous backing sheet in contact with said projecting loop portions, substantially co-extensive with said netting, and attached in spaced relation thereto in a plane parallel to 40 the plane of the netting.

10. A lath comprising a wire netting formed with projections on one side thereof, a flexible backing sheet for said netting in contact with said projections and in spaced relation to the major portion of the netting, fastening means passing through the backing sheet and engaging said projections to connect said netting and said backing sheet, and a non-absorptive material on the 50 surface of said backing adapted to seal openings therein around said fastening means.

WILLIAM D. HICKS.
